CLAIM

I claim the ornamental design for a modular beehive with lid, as shown.

DESCRIPTION

FIG. 1 is a front-top perspective view of an embodiment of my design including a top lid and a bottom lid.

FIG. 2 is a bottom plan view of the embodiment of FIG. 1.

FIG. 3 is a top plan view of the embodiment of FIG. 1.

FIG. 4 is a front elevational view of the embodiment of FIG. 1.

FIG. 5 is a right side elevational view of the embodiment of FIG. 1.

FIG. 6 is a rear elevational view of the embodiment of FIG. 1.

FIG. 7 is a left side elevational view of the embodiment of FIG. 1.

FIG. 8 is a rear-bottom perspective view of the embodiment of FIG. 1; and,

FIG. 9 is an exploded top-front perspective view of the embodiment of FIG. 1.
